UNITED STATES PATENT OFFICE.

JOSEPH C. HOSHOR, OF PATERSON, NEW JERSEY, ASSIGNOR TO HIMSELF
AND THOMAS E. PLATT, OF SAME PLACE.

CONVEYER.

SPECIFICATION forming part of Letters Patent No. 674,382, dated May 21, 1901.

Application filed August 21, 1900. Serial No. 27,561. (No model.)

To all whom it may concern:

Be it known that I, JOSEPH C. HOSHOR, a citizen of the United States, residing at Paterson, in the county of Passaic and State of 5 New Jersey, have invented an Improvement in Conveyers, of which the following is a specification.

My invention relates to improvements in conveyers for coal, ore, grain, and other articles of merchandise, the objects being to construct the links of the chain alike, to reduce the wear by increasing the bearing-surfaces, and to cause the conveyer to run smooth and even with the weight and strain distributed.

15 In carrying out my invention the gravity-buckets are provided with end frame-plates and pivot-pins, and the said buckets and the cross-rods between the same are pivoted to the ends of the links forming the conveyer-chain, and the rollers or wheels of the said conveyer are between the links of each pair and midway between their ends, and the pivotally-connected ends of the links are not the pivotal bearings of the rollers or wheels. The 25 links are each made with a single eye-plate at one end and two eye-plates at the other end, spaced apart to receive the single eye-plate of the next link, and I prefer to employ eye-blocks between the pivotal ends of the 30 links to space them apart a sufficient width to receive the rollers or wheels.

In the drawings, Figure 1 is an elevation of a conveyer illustrative of my invention. Fig. 2 is a plan representing two buckets and the 35 portions of the conveyer-chain to which the same are pivoted. Fig. 3 is a side elevation of the parts shown in Fig. 2. Fig. 4 is a cross-section of the parts shown in Figs. 2 and 3 between the pivots, and Fig. 5 represents one 40 end of a bucket with the side frame and pivot-pin and a section through the connected links adapted to surround and to carry the said pivot-pin. Figs. 2 to 5, inclusive, are shown of exaggerated size for clearness.

45 The frame *a*, illustratively shown in Fig. 1 and supporting the conveyer, may be of any desired construction. *b* represents the motor-wheel, and *b'* the guide-wheels, in suitable bearings connected to the said frame and 50 around which the conveyer extends.

c represents the conveyer-chain; *c'*, the roll-

ers or wheels between the pairs of links of the conveyer-chain upon axles 1; *d*, the gravity-buckets, and *d'* the pivot-pins of the gravity-buckets, preferably connected to said frame-plates *h*, secured upon the ends of the gravity-buckets. The rollers or wheels *c'* run upon the tracks *e e'*, the tracks supporting the horizontal portions of the conveyer. In this device the pivots of the buckets and the ends 55 of the cross-shafts are pivotally connected to the ends of the links of the conveyer-chains, and the rollers are pivoted to and between the links of each pair and midway between their ends. This construction imparts a new 60 relation between the conveyer-chains and said motor and guide wheels, (shown in Fig. 1,) in which the rollers pass around the wheels with the pivots of the links free of contact with said wheels and with the links occupying 65 positions parallel to tangential peripheral lines of said wheels. By this construction the traveling movement of the links is easier, with greater freedom and flexibility, than where the rollers are pivoted at the pivots of 70 the links, as in the old way.

The conveyer-chain is composed of links *f*, in pairs, the links being all alike and each link being made with a single eye-plate 2 at one end and two similar eye-plates 3 at the 75 other end, spaced apart to receive the single eye-plate 2 of the next or adjacent link. The said eye-plates in connecting up the similar links surround the sleeves *i* and turn thereon, and between the connected eye-plates of 80 the links I prefer to place eye-blocks 4 of a width to space apart the links *f* to receive the rollers or wheels *c'*, pivoted upon axles 1, passing through the links midway between the respective ends of the links.

85 The pivot-pins *d'* of the gravity-buckets are received by sleeves *i* at the junction of the links of the conveyer, and the cross-shaft *g*, placed intermediate to the gravity-buckets, is provided with reduced ends, also received in sleeves at the junction of the links of the conveyer. Consequently the links are 90 pivoted together by the sleeves *i* at the ends of the cross-shaft *g* and at the pivot-pins of the buckets, and the rollers or wheels do not 95 come at the pivots of the chains, but are independent of these pivots and come interme- 100

diate to the pivots and midway between the ends of the links of the chain and between the links of each pair upon independent axes, and in this manner the weight and strain of 5 the conveyer and buckets are more evenly distributed.

I claim as my invention—

1. In a conveyer, the combination with the gravity-buckets having end pivots and a shaft 10 extending across between the buckets, of the conveyer-chains having links pivoted respectively to the pivots of the buckets and the ends of the intermediate cross-shaft, and wheels or rollers pivoted between the links of 15 each pair and midway between their ends and independent of the pivots of the buckets or cross-shaft, substantially as set forth.
2. In a conveyer, the combination with the gravity-buckets having end pivots connected 20 thereto and a cross-shaft between the respective buckets, of the conveyer-chains each composed of similar pairs of links connected pivotally at their ends to the pivots of the buckets and the respective ends of the intermediate cross-shaft, the links of the chains 25 being similar and each one provided with a single eye-plate at one end and two similar eye-plates at the other end spaced apart to receive the single eye-plate of the next or adjacent link and the rollers or wheels pivotally connected upon axles 1 between the links of each pair and midway between the respec-
3. In a conveyer, the combination with the gravity-buckets having end pivots connected thereto and a cross-shaft between the respective buckets, of the conveyer-chains each composed of similar pairs of links connected pivotally at their ends to the pivots of the 40 buckets and the respective ends of the intermediate cross-shaft, the links of the chains being similar and each one provided with a single eye-plate at one end and two similar eye-plates at the other end, spaced apart to 45 receive the single eye-plate of the next or adjacent link and the rollers or wheels pivotally connected upon the axles 1 between the links of each pair and midway between the respective ends of the links, and sleeves passing through the eye-plates at the ends of the links and to which the links are pivoted and which sleeves receive the pivot-pins of the buckets and the ends of said cross-shaft, and eye-blocks between the connected ends of said 50 links and surrounding said sleeves, substantially as set forth.

55

Signed by me this 16th day of August, 1900.

JOSEPH C. HOSHOR.
